US00D973706S

(12) **United States Design Patent** (10) Patent No.: **US D973,706 S**
(45) Date of Patent: **** Dec. 27, 2022**

(54) **DISPLAY SCREEN OR PORTION THEREOF
WITH GRAPHICAL USER INTERFACE**

- (71) Applicant: **Apple Inc.**, Cupertino, CA (US)
(72) Inventors: **William Martin Bachman**, San Jose, CA (US); **Colin Bennett**, San Francisco, CA (US); **Alan C. Dye**, San Francisco, CA (US); **Alexander C. D. Fringes**, San Francisco, CA (US); **Monika E. Gromek**, Oakland, CA (US)
(73) Assignee: **Apple Inc.**, Cupertino, CA (US)
(**) Term: **15 Years**
(21) Appl. No.: **29/820,997**
(22) Filed: **Dec. 27, 2021**

Related U.S. Application Data

- (63) Continuation of application No. 29/754,109, filed on Oct. 6, 2020, now Pat. No. Des. 939,560, which is a continuation of application No. 29/733,240, filed on Apr. 30, 2020, now Pat. No. Des. 906,367, which is a continuation of application No. 29/714,673, filed on Nov. 25, 2019, now abandoned, which is a continuation of application No. 29/655,857, filed on Jul. 9, 2018, now Pat. No. Des. 868,105, which is a continuation of application No. 29/606,435, filed on Jun. 5, 2017, now Pat. No. Des. 822,711.

CLAIM

The ornamental design for a display screen or portion thereof with graphical user interface, as shown and described.

DESCRIPTION

The FIGURE is a front view of a display screen or portion thereof with graphical user interface showing the claimed design.

The dashed broken lines in the FIGURE show a display screen or portion thereof, and form no part of the claimed design.

The dot-dash broken lines in the FIGURE and the areas within the dot-dash broken lines show portions of the graphical user interface that form no part of the claimed design.

1 Claim, 1 Drawing Sheet
